UNITED STATES PATENT OFFICE.

CARLTON SAGE, OF ELKHART, INDIANA.

URETHRAL POWDER-APPLIER.

SPECIFICATION forming part of Letters Patent No. 398,904, dated March 5, 1889.

Application filed June 29, 1888. Serial No. 278,546. (No model.)

To all whom it may concern:

Be it known that I, CARLTON SAGE, of Elkhart, in the county of Elkhart and State of Indiana, have invented a certain new and useful Urethral Powder-Applier, of which the following is a specification.

My invention relates to the application of powdered medicines within the male urethra; and it consists in a novel construction of the same, as hereinafter set forth and claimed.

In the drawings, Figure 1 is a perspective view of my improved device preparatory to the insertion of the medicine; Fig. 2, a vertical sectional view showing the device ready for insertion into the interior of the diseased part, and Fig. 3 a detail view.

The object of the invention is to produce a device that will successfully apply a dry powder to deep canals in the body, and this I accomplish by the construction which I have shown, and which will now be described in detail.

A indicates a hollow tubular shell, open at its ends and preferably, though not necessarily, made cylindrical in cross-section. At the upper end the tubular shell is provided with an enlarged head, B, as shown in Figs. 1 and 2, the said head being provided with a central, preferably conical, opening, forming a sort of funnel, and communicating with the interior of the tubular shell.

C indicates a screw which passes through one wall of the head B, and is provided at its outer end with a milled head or crank, and at its inner end is preferably reduced in diameter, as shown in Fig. 2, for a purpose presently explained.

When the instrument is to be inserted, it is necessary to close the lower end of the tubular shell, and to secure this result I place within the shell a rod, D, as shown in Fig. 2, the said rod being notched near its upper end, as at a, to receive the end of the screw C.

After the instrument is inserted the screw is drawn out of engagement with the notch in the rod D, and the latter is withdrawn from the tubular shell, the said shell of course remaining in the canal or passage to be treated.

E indicates an elongated screw or conveyer adapted to be inserted into the tubular shell after the withdrawal of the rod D, the said conveyer being formed with a circumferential groove, b, to receive the end of the screw C, this construction permitting the rotation of the conveyer E, but preventing longitudinal movement of the latter within the tubular shell or case.

The powder is placed within the funnel-shaped head B, and is fed or forced through the tubular shell and discharged at the end thereof by merely turning the conveyer E by means of its milled head or crank.

The material of which the instrument is made may obviously be varied, as may also its design.

An agitator of any suitable description may be applied to the screw E to work within and stir up the powder in the cup B.

I do not wish to be understood as limiting myself to the use of a straight tube and screw, as it is apparent that the lower end of the tube may be bent or curved slightly, in which case the screw would have to be made of a flexible material.

Having thus described my invention, what I claim is—

1. In a urethral powder-applier, the combination, with shell A, having hollow head B, of the interchangeable devices D and E, and a retaining device for the latter.

2. In a urethral powder-applier, the combination, with shell A and head B, of a rod, D, provided with notch a, and a retaining device for the rod.

3. In a urethral powder-applier, the combination, with the shell A and head B, of a conveyer, E, provided with groove b, and a retaining device permitting rotary but not longitudinal motion of the conveyer.

In witness whereof I hereunto set my hand in the presence of two witnesses.

CARLTON SAGE.

Witnesses:

SILAS BEERUP,
C. L. THOMAS.
